UNITED STATES PATENT OFFICE.

BURR STRUBLE, OF PORTLAND, OREGON.

CASTING MACHINE.

Application filed May 21, 1923. Serial No. 640,484.

To all whom it may concern:

Be it known that I, BURR STRUBLE, a citizen of the United States, residing at Portland, county of Multnomah, State of Oregon, have invented certain new and useful Improvements in Casting Machines, of which the following is a specification.

My invention relates to casting machines in general, and particularly to dental casting machines, the object being to provide dentists with a cheap, simple and convenient casting machine, to provide means whereby the maximum pressure of air upon the mold may be predetermined by a setting of the machine parts, to provide a storage chamber intermediate the air pump and the mold whereby compressed air at said maximum pressure may be applied to the mold and allowed to be gradually reduced to atmospheric pressure, and to provide improved gasket means of making an air tight joint between said storage chamber and the mold.

I accomplish the above objects, and other desirable results that will hereinafter appear, by means of the construction illustrated in the accompanying drawing, which is a part of this application for Letters Patent, like characters of reference indicating like parts throughout the several views thereof, and in which:

Fig. 1 is a side elevation of my device.

Fig. 2 is a sectional elevation thereof.

Fig. 3 is a plan view thereof, with the operating parts swung to one side.

Fig. 4 is a plan view thereof with the operating parts in operating position.

Fig. 5 is a section upon line 5—5 of Fig. 2.

Fig. 6 is a perspective view of a portion of the standard.

Fig. 7 is a perspective view of the swinging arm.

Fig. 8 is a plan view of one of the retaining rings.

In general my device consists of a mold receiving base having a standard arising therefrom, a swinging arm mounted upon said standard, a vertically movable pump cylinder mounted in said arm, a piston within said cylinder, a storage chamber upon said piston, and a head upon said storage chamber adapted to contact with the mold in an air tight manner.

In the base 9 of my device I provide a series of concentric counterbores 10 adapted to receive various sizes of molds. In Fig. 2 is shown the smallest size of mold 11, and

in Fig. 1 is shown an intermediate size of mold 12. The molds are of the usual form of dental mold, as shown in Fig. 2, and need no description herein. Arising from the base 9 is a standard 13 securely fixed within the base, and provided near the top thereof with a fixed collar 14. Upon the upper portion of said standard above the collar 14, and resting upon said collar, is rotatably mounted a swinging arm 15, with a hub 15^a at the extremity thereof, said hub being adapted to be swung about the standard 13 until it assumes a position axially above the counterbores 10 in the base, as shown in Figs. 1, 2 and 4.

Freely mounted both vertically and rotatably within said hub 15^a is a pump cylinder 16, open at its lower end and closed at its upper end, with a hand knob 17 mounted upon the upper end thereof, as shown in Figs. 1 and 2. As will hereinafter appear it is desirable that said pump cylinder should rotate very freely within said hub 15^a but should present some frictional resistance to vertical movement therein, and this I accomplish by providing rings 18 disposed within an annular slot 19 in said hub, said rings gripping the pump cylinder with sufficient force to provide the desired frictional resistance to vertical movement thereof, but rotating freely within the groove 19 and thus presenting no resistance to rotation of the pump cylinder.

Within the pump cylinder 16 I provide the usual piston 20 with pump washer 21, as shown in Fig. 2, and extending downward from said piston, and integral therewith, is a cylindrical storage chamber 22 terminating in a head 23, which head is counterbored to receive an annular gasket or washer 24, as shown in Fig. 2. Said washer 24 contacts with the mold 11 when the chamber 22 is in its lowermost position, and is adapted to make an air tight connection between said chamber and the mold. Preferably said washer is constructed of cardboard, and is soaked in water before using, and it is one of the features of my invention that such soaking is easily accomplished without removing the washer from the head 23, by simply slipping the arm 15 together with the pump cylinder 16 and chamber 22 from the standard 13 and dipping the head 23 in water.

To locate the swinging arm 15 exactly axially above the mold 11 I provide a stop

pin 25 in the collar 14 to contact with said arm when the latter is in operating position, and to secure the arm in said position I provide therein a spring catch 26, the end of which catch is adapted to enter a hole 27 in said collar 14.

To prevent the chamber 22 being completely withdrawn from the pump cylinder 16 I provide within said cylinder a rod 28 extending downward through the piston 20 and terminating within the chamber 22 with a nutted end 29, the nut of which will contact with the piston 20 to retain the chamber within the pump cylinder. The orifice 15 in the piston through which rod 28 passes is made larger than said rod to admit air from the pump cylinder into the chamber 22.

To operate the device the arm 15 is swung 20 to one side as shown in Fig. 3, and the mold is placed in position within the counterbore in the base 9, as shown in Figs. 1 and 2. The pump cylinder, chamber and head 23 are raised as a unit by sliding the pump cylinder within the hub 15^a into position shown by dotted lines 30 in Fig. 2. The chamber 22 is made a sufficiently tight fit within the pump cylinder 16 to act as a unit therewith when being thus raised thereby.

30 The arm 15 is then swung back into its position over the mold 11, and the pump cylinder, chamber and head 23 depressed until the washer 24 contacts with the mold 11, as shown in Fig. 2, the chamber 22 having previously been partially withdrawn from the pump cylinder, as also shown in Fig. 2. A further depression of the pump cylinder will result in compressing the air therein and causing the compressed air to 40 enter the chamber by way of the orifice in the piston through which the rod 28 passes.

It is obvious that by this construction the piston cannot be brought into such close juxtaposition with the mold as to expel 45 thereupon all the compressed air within the device, but on the contrary simply compresses the air within the chamber 22, which thereupon is slowly dissipated through the mold until the pressure within the chamber 22 returns to that of the atmosphere. This is one of the principal features of my invention, since it has been found detrimental to the casting process to bring the piston into close juxtaposition with the mold and 55 thus subject the mold to a momentarily high pressure which quickly is reduced to atmospheric pressure. It has been found that the pressure should be raised only to a predetermined value, and then allowed to dissipate slowly through an appreciable interval of time until it is again at atmospheric pressure, thus allowing the casting such interval of time in which to become solidified before all pressure is removed therefrom. 60 This is accomplished by my construction,

since the air within the chamber 22 is brought to a certain pressure by moving the pump cylinder downward thereupon, said certain pressure being regulated by the amount that the chamber 22 has previously 70 been withdrawn from the pump cylinder 16, and the air within the chamber 22 having been so compressed an interval of time is required for its dissipation through the mold and the return to atmospheric pressure 75 within the chamber. During this interval of time the casting becomes solidified.

I provide means for predetermining the maximum pressure to be used by engraving, or otherwise mounting, a scale upon the chamber to indicate such settings of the chamber within the pump cylinder as correspond to certain maximum pressures that may be obtained with such setting. In Figs. 1 and 2 such scale is illustrated by lines scribed upon the chamber 22 as shown at 31, each line adapted to register with the bottom of the pump cylinder at respective positions of the chamber 22, and each line being stamped with the pressure that will result should the chamber be set at the position where such line registers with the bottom of the pump cylinder.

For example: In Fig. 2 the chamber is shown with the head 23 in contact with the mold and the bottom of the pump cylinder set at the line marked 6. Should the pump cylinder now be depressed quickly until the bottom thereof contacts with the head 23, as shown by dotted lines 32, the maximum pressure within the chamber resulting will be six pounds above atmosphere. No greater pressure than six pounds can be obtained within the chamber 22 with this setting of the chamber within the pump cylinder, and thus the maximum pressure upon the mold is predetermined by such setting. Furthermore, the volume of air within the chamber 22 having been brought up to a pressure of six pounds, or whatever pressure may have been predetermined, the mold will be retained under pressure for such an interval of time as is required for the air within the chamber 22 to seep through the mold and thus return the pressure within said chamber to atmosphere. During this interval of time the casting will have solidified under pressure.

A further feature of my invention is the swinging of the pump and chamber 22 away from directly over the mold, thus leaving the latter unhoused, and in a convenient position for reception of the metal within the crucible portion of the mold, and the application of blow torch to the metal to melt the same.

My device may be made of any size, and constructed of any materials deemed convenient and suitable for a device of this character, and while I have illustrated and

described a form of construction and arrangement of parts found desirable in materializing my invention, I wish to include in this application all mechanical equivalents and substitutes that may fairly be considered to come within the scope and purview of my invention as defined in the appended claims.

Having disclosed my invention so that others may be enabled to construct and to use the same, what I claim as new, and desire to secure by Letters Patent is:

1. In a casting machine to operate a mold: an air pump; and a storage chamber upon the piston of said pump and disposed intermediate the mold and said air pump.

2. In a casting machine to operate a mold: an air pump; a storage chamber upon the piston of said pump and disposed intermediate said mold and said air pump; and a head upon said chamber adapted to contact with the mold.

3. In a casting machine: a mold receiving base; a standard mounted within said base; an arm rotatably mounted upon said standard; an air pump cylinder mounted upon said arm; a piston within said cylinder; a chamber upon said piston; and a mold engaging head upon said cylinder.

4. In a casting machine for operating a mold: an air pump cylinder and a cylindrical storage chamber coaxially and relatively slidably mounted above the mold.

5. In a casting machine for operating a mold: an air pump cylinder slidably mounted above the mold and coaxial therewith; and a storage chamber slidably mounted within said cylinder and adapted to make an airtight connection with the mold.

6. In a casting machine for operating a mold: an air pump cylinder and a storage chamber relatively slidable and coaxially mounted above the mold; and pivotal means for mounting said cylinder and said chamber as a unit above the mold, whereby said unit may be swung away from the mold.

7. In a casting machine for operating a mold: a mold receiving base; a pump cylinder; a storage chamber coaxially mounted within said pump cylinder; a head upon said chamber adapted to contact with the mold; a pivotally mounted swinging arm to mount said pump and said chamber above the mold; and positioning means for securing said arm in position wherein said cylinder and said chamber are coaxially above the mold.

8. In a casting machine: an air pump cylinder; a piston within said cylinder; a chamber upon said piston and projecting from one end of said cylinder; and a scale of air pressures upon said chamber.

9. In a casting machine: a coaxially mounted relatively slidable pump cylinder and storage chamber; and a scale to indicate the pressure within said chamber resulting from a certain movement of said cylinder thereupon.

10. In a casting machine: an air pump cylinder, a storage chamber, and a mold engaging head containing a washer, all mounted as a unit; and means to mount said unit upon a mold in a removable manner.

In witness whereof I claim the foregoing as my own I hereunto affix my signature at Portland, county of Multnomah, State of Oregon, this 16th day of May 1923.

BURR STRUBLE.
